Primary Examiner — Mitchell Siegel(74) *Attorney, Agent, or Firm* — Nicholas J. Aquilino(57) **CLAIM**

The ornamental design for a golf grip, shown and described.

DESCRIPTION

FIG. 1 is a perspective view of a golf grip showing my new design.

FIG. 2 is a front elevational view thereof.

FIG. 3 is a side elevational view thereof.

FIG. 4 is a rear elevational view thereof.

FIG. 5 is a top plan view thereof.

FIG. 6 is a bottom view thereof.

FIG. 7 is a perspective view of an alternative design of the golf grip.

FIG. 8 is a perspective view of a second alternative design of the golf grip; and,

FIG. 9 is a perspective view of a third alternative design of the golf grip.

The broken line showing of the medallion (FIG. 1) and the fragmented shaft (FIGS. 1-4) are included for the purpose of illustrating and forms no part of the claimed design.
